UNITED STATES PATENT OFFICE.

EUGENE DRAHONOVSKY, OF MILWAUKEE, WISCONSIN.

CARBURETER.

1,371,302.

Specification of Letters Patent. Patented Mar. 15, 1921.

Application filed June 2, 1919. Serial No. 301,148.

To all whom it may concern:

Be it known that I, EUGENE DRAHONOVSKY, a citizen of the United States, and resident of Milwaukee, in the county of Milwaukee and State of Wisconsin, have invented new and useful Improvements in Carbureters, of which the following is a description, reference being had to the accompanying drawings, which are a part of this specification.

10 My invention relates to certain new and useful improvements in carbureters wherein the fuel and air will be thoroughly co-mingled prior to their entrance into the intake manifold, and has for one of its objects to provide a floating valve member operated by the suction created in the mixing chamber of the carbureter by the engine which will automatically supply air in the proper proportions relative to the speed of the engine.

15 Another object of the present invention is to provide a carbureter having means for metering the air and at the same time directing it into the venturi to effect a thorough comingling of the air and fuel.

20 A further object of this invention is to provide a carbureter which will be of compact construction, efficient in operation and comparatively inexpensive of production, all things being considered.

25 A still further object of the present invention is to provide a carbureter embodying the various features herein set forth which will be compact, simple and efficient in operation.

30 With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

35 In the accompanying drawing, I have illustrated one complete example of the physical embodiment of my invention constructed according to the best mode I have so far devised for the practical application of the principles thereof, and in which—

The single figure represents a view, part in section and part in elevation of a carbureter embodying my invention.

40 Referring now more particularly to the accompanying drawing, 2 designates a body casing provided medially of its ends with a

laterally extending annular flange 3 for closing the upper end of a float chamber 4 secured about the lower portion of the body casing by means of a nut 5 engaging the lower threaded nippled end 6 of the body casing. The body casing is open throughout its length and has its hollow nippled end 6 communicating with a base member 7 secured thereto by means of a bolt 8 engaging the bottom wall of the base member and having its upper threaded end engaged in the centrally threaded bore of a spider member 9, formed in the body casing near its bottom end, the cross arms 10 of the spider 9 being bored to provide fuel passageways 11 communicating with the fuel passageway 12 extending upwardly into the body casing and terminating in a cup-shaped fuel outlet 13. The casting 7 has an air inlet 14 provided with a butterfly valve 15 fixed to a journaled shaft 16 and adapted to be operated as hereinafter described, and with an auxiliary air inlet 17 adapted to be connected with a stove surrounding the intake manifold (not shown), but in the present instance being illustrated as closed by a plate member 18.

45 Disposed above the body casing 2 is a member 19 which has a sleeve 20 adapted to slip into the upper end of the body casing which is counter-bored to provide a snug fit therewith and is secured to the body casing by means of a flange 21 abutting a flange 22 formed on the body casing, any desired means such as cap screws or the like may be used to secure the body casing 2 and member 19 together. The member 19 has its wall flared upwardly and inwardly to provide a substantially conical shaped mixing chamber 23 communicating with the body casing by means of a valve chamber 24 in which is disposed a floating valve member 25 to be later described. The member 19 has its upper end provided with a flange 26 for securing to the intake manifold of an internal combustion engine (not shown), and has journaled in the upper end thereof a rod 27 carrying a butterfly valve 28, the shaft 27 being provided with an operating or throttle arm 29, carrying at its outer end an adjustable lever 30 adapted to be connected with the controlling lever (not shown), and with an adjustment 31 to limit the closing of the butterfly valve 28.

50 The float chamber 4 is in communication with a suitable fuel supply (not shown) and a float member 32 operating a control valve

(not shown) in said fuel supply for maintaining the fuel in the float chamber at a constant level, and as before stated the fuel passes from the float chamber from passage-
ways 11 and then up through outlet 12, a
needle valve 33 being disposed in the outlet
12 just below cup 13 for governing the
amount of fuel passing outwardly of the fuel
outlet. The needle valve 33 has its shank
34 passed outwardly and upwardly of the
body casing through a centrally bored sleeve
35 formed integral with the body casing and
provided near its outer end with the counter-
bored recess 36.
15 The position of the needle valve 33 relative to its seat is capable of fine adjustment by the means to be hereinafter described, and for normally yieldingly urging the needle valve to the thus adjusted position, I employ an extension spring 37 surrounding the portion of the shank 35 disposed in the recess 36, said spring having one end pressing against a collar 38 and its other end pressing against the outer end of
20 a cap 39 which has its inner end reduced and threaded as at 40 to engage the outer threaded end 41 of the recess 36, this construction at all times yieldingly urging the needle valve 33 inwardly as will be obvious.
25 The cap 39 also serves to secure to the body casing a bracket member 42 provided at one end with a pair of spaced ears 43 between which is disposed and pivoted as at 44 a rocking lever 45, said lever being provided with a recess 46 surrounding the shank 34 of the needle valve, and of greater diameter than said shank, and having its end outwardly of said opening threaded as at 47 to receive an adjusted screw 48 having
30 its inner end adapted to abut the end 49 of the bracket 42, and its other end provided with a knurled head 50, a locking screw 51 being provided to retain the adjusted screw 48 from accidentally changing from its ad-
35 justed position.
40 The end of the needle valve shank 34 outwardly of the lever 45 is threaded to receive a knurled nut 52 having a bowl-shaped portion 53 adapted to engage the arm about the opening 46 to provide a universal or ball and socket joint connection between the lever 45 and the valve shank 34, a locking nut 54 being provided to lock the knurled nut 52 in adjusted position. By this con-
45 struction it will be readily apparent that to obtain the desired adjustment of the needle valve 33 it is necessary to merely adjust screw 48 which will govern the space be-
50 tween the needle valve 33 and its seat, and
55 that when the lever 45 is rocked on its pivot to compress spring 37, and move the needle valve out of the passageway 12 for supply-
60 ing a rich mixture when it is desired to start the engine. When it is desired to com-
65 pletely close the needle valve 33, the adjust-

ing screw 48 is unscrewed until its inner end is free from the end 49 of the bracket 42 and the needle valve will then be urged into engagement with its seat by means of spring 37, and the collar 38, which has its inner surface tapered, will engage the tapered seat 38' at the inner end of recess 36 and prevent the leakage of fuel thereby.

Loosely journaled on one end of the shaft 16 is a two-arm lever 55 provided on its inner face adjacent shaft 16 with a stud 56, having coiled thereabout one end of a spring 57 which has its other end coiled about shaft 16 in an opposite direction and then secured thereto as at 58. When the lever 55 is rocked in a clockwise direction with reference to the drawing, the spring 57 will cause the rod 16 to rotate in a clockwise direction and thus close the inlet 14 by means of the valve 15, and should the lever 55 be moved farther after the valve 15 is in closed position, the spring 57 will yield to permit this further movement. The means hereinafter described are provided for operating the needle valve against its spring 37 when the lever 55 is moved after the valve 15 is closed.

This means includes an arm 59 which is pivoted near one end as at 60 to the end 61 of the lever 45 and has its end remote from its pivot 60 connected to one arm 62 of the lever 55 by means of a link connection 63, and when the lever 55 is rocked the arm 59 will be moved on its pivot. Formed on the end of arm 59 adjacent its pivot 60 is a projection 64 adapted to abut the lever 45 after a certain limit of movement of said arm and if the arm 59 is moved beyond this limit of movement, it then forms a rigid part of lever 45 by means of the projection 64 engaging said lever, and this rocks the lever 45 on its pivot 44 to move the needle valve as hereinbefore described. Leading from the arm 62 of the lever 55 is a control wire or other means 65 adapted to be connected to the dash board and leading from the other arm 62 of the lever 55 is a control wire 65' adapted to be passed outwardly of the radiator so that the butterfly valve 15 and the needle 34 may be operated either from the driver's seat or from the forward end of the machine.

Referring now more particularly to the novel form of air controlled valve which I employ, 66 represents a Venturi tube which is flared outwardly toward its upper end and has its upper end laterally flanged as at 67 and engaging lugs 68 on the inner wall of the body casing to centrally suspend the Venturi tube therein, the lower end of the tube being spaced about the cup outlet 13. When running at low speed, sufficient air will pass through the Venturi tube 66 and will mingle with the fuel from outlet 13 and then pass upwardly into the mixing chamber, but when the engine is speeded

up the opening surrounding the outlet 13 is sufficient to accomodate the volume of air necessary to complete the proper mixture and so I provide a plurality of spaced apertures 69 in the flange 67 to supply this increased amount of air.

The valve 25 governs or controls the air passageways 69 and is of ring shape and is annularly grooved as at 70, whereby its walls 71 defining said groove will close the aperture 69 when the valve 25 is inoperative. As the engine's speed is increased the suction created thereby in the mixing chamber 23 is proportionately increased and will consequently raise valve 25, permitting air in proportionate amount to pass through the apertures 69 and the air passing through the apertures will press against the top closed wall of the groove 70 and be then directed downwardly into the Venturi tube a short distance and engage with the fuel and air passing upwardly therethrough. The fuel and air then pass through the central passageway in the valve 25 into the mixing chamber 23 which by reason of its shape, imparts to the air and fuel vapors a whirling or eddying motion, thus insuring the thorough co-mingling of the fuel and air.

In order to insure the instant return of valve 25 to its position closing apertures 69 when the engine's speed is reduced, I provide in the top wall of the valve three or four pin openings 72 which while sufficient to allow the valve 25 to drop to its inoperative position, it will be insufficient to allow air in any volume to pass therethrough when the engine is running at low speed. The upper movement of valve 25 is restricted or limited by means of the annular shoulder 73 formed in the member 19 and as will be obvious, the adjustment of the volume of air supplied at the various engine speeds is governed by inserting in the valve chamber 25, valves of various weights which will be best adapted to the particular engine with which the carbureter will be used.

From the foregoing description taken in connection with the accompanying drawing, it will be readily apparent that I have designed a carbureter which will be practical for the purposes described.

What I claim as my invention is:

1. A carbureter for internal combustion engines comprising a body casing, a mixing chamber disposed above the body casing, a fuel inlet within the body casing, a Venturi tube having its upper end laterally flanged and secured to the wall of the body casing adjacent the mixing chamber and its lower end surrounding the fuel inlet, the flange of said Venturi tube being apertured, and an annularly channeled sleeve disposed above

the Venturi tube for controlling the passage of air through the apertured flange of the Venturi tube, said sleeve deflecting the air passing through the apertured flange into the Venturi tube whereby the thorough comingling of the air and fuel is obtained.

2. A carbureter for internal combustion engines comprising a body casing, a fuel inlet, a Venturi tube disposed over the fuel inlet, air passageways surrounding the Venturi tube, and an annularly channeled ring of substantially inverted U-shape in cross section slidably mounted above the Venturi tube for controlling the passage of air from said passageways, said ring being controlled by the suction caused in the mixing chamber by the internal combustion engine and deflecting the air passing from said passageways into the mouth of the Venturi tube to be comingled with the fuel passing upwardly therethrough.

3. A carbureter for internal combustion engines, comprising a body casing, a mixing chamber disposed above the body casing and having its wall restricted toward its upper end, a valve chamber intermediate the body casing and the mixing chamber, a Venturi tube extending into the body casing from the valve chamber, air passageways surrounding the Venturi tube and communicating with the valve chamber, and a sleeved valve of inverted U-shape in cross section for controlling said passageways, said valve being controlled by suction created in the mixing chamber and having small apertures in its top wall to permit its drop by gravity when the suction in the mixing chamber decreases.

4. A carbureter for internal combustion engines, comprising a body casing, a mixing chamber, a valve chamber intermediate the body casing and the mixing chamber and provided with an inner peripheral wall of the same diameter throughout, a Venturi tube having its upper end flanged and secured adjacent the bottom of the valve chamber to the body casing wall and its lower end spaced about the fuel inlet, said upper flanged end being provided with a plurality of spaced apertures providing air passageways, an annularly grooved valve sleeve slidably mounted in the valve chamber and adapted to control the air passageways and deflect the air passing therethrough into the Venturi tube, means limiting the upward movement of the valve, and means permitting the ready return of the valve to its position closing the air passageways.

In testimony whereof, I affix my signature.

EUGENE DRAHONOVSKY.
